YOKE PRESS

Raymond J. Gabler, Kansas City, Mo., assignor to
 Butler Manufacturing Company, Kansas City,
 Mo., a corporation of Missouri

Application October 13, 1939, Serial No. 299,310

3 Claims. (Cl. 38—13)

My invention relates to a yoke press and more particularly to a yoke press for finishing the yoke and collar of shirts such as men's shirts in laundries and the like.

One object of my invention is to provide a yoke press having a one piece buck.

Another object of my invention is to provide a heated collar form which will aid in drying moisture not removed from the collar during the pressing operation.

Another object of my invention is to provide a yoke press in which the buck is more easily repadded.

Another object of my invention is to provide a yoke press having a collar clamp which need not be removed in order to repad the buck.

Other and further objects of my invention will appear from the following description.

In the accompanying drawings which form part of the instant specification and are to be read in conjunction therewith and in which like reference numerals are used to indicate like parts in the various views.

Figure 1 is a front elevation of a yoke press showing one embodiment of my invention.

Figure 2 is a side elevation of the yoke press shown in Figure 1.

Figure 3 is a fragmentary top plan view on an enlarged scale, of the yoke press shown in Figures 1 and 2.

Figure 4 is a sectional view taken on the line 4—4 of Figure 3.

Figure 5 is a fragmentary view of a collar clamping mechanism on an enlarged scale.

Referring now to the drawings, a standard 1, on any suitable pedestal 2, supports a frame 3, to which is pivoted an arm 4 operated by a hand lever 5. The arm 4 and the hand lever 5 are adapted to pivotally and operatively support a pressing head 6 which cooperates with the yoke 7 of the press. Steam from any suitable source is piped through pipe 8, through check valve 9 to manifold 10, through pipe 11 to the interior of the buck 7 and through flexible steam pipe 12 to the head 6. A counter-balancing spring 13 is secured to the pedestal 2 by means of hook 14 and to the outboard portion 15 of the arm 4 by means of a connecting rod 16. A collar clamping mechanism indicated generally in Figures 1 and 2 by the reference numeral 17, is shown in greater detail in Figures 3, 4, and 5. A hitch rod 18 is adapted to operate the collar clamping mechanism through pivoted, foot operating lever 19.

The details of the mechanism for operating

the pressing head through operating arm 5 form no part of the instant invention and it is understood that any suitable pressing mechanism for operating the pressing head may be employed in connection with my invention.

The majority of the collar forms of the yoke presses of the prior art are not heated and, if heated, require a separate casing and a separate steam lead. In the prior art, the collar clamps have to be removed in order to repad the buck. It will be readily understood that, after use, the buck padding must be renewed from time to time. Failure to renew the padding will result in poor pressing and frequently in soiling the shirts being pressed.

The salient features of my invention reside in the collar clamping mechanism and the buck construction, enabling me to use a heated collar form and to renew the buck padding without the necessity of removing the collar form.

Referring now to Figures 3, 4, and 5, it will be readily seen, from Figure 4, that the buck 7 is provided with an integral extension 20 so that, when steam is admitted to the interior 21 of the buck 7, it will heat the collar form 20, as well as the buck proper. The collar clamp proper comprises a pair of arms 22 and 23, pivotally mounted upon stud bolts 23' and 24, supported by a standard 25, which may be an integral part of the buck, as shown. The collar clamp arms 22 and 23 are normally urged to clamping position by a spring 26, as can readily be seen by reference to Figures 4 and 5. Depression of the operating pedal 19 pivots the arms outwardly to the dotted line positions shown in Figure 5, against the action of the spring 26. The buck padding 27 is firmly secured in the region of the collar form by means of a band 28. This band makes direct metal to metal contact with the collar form buck extension 20 so that the heat of the buck will be transmitted to the band 28. The ends of the band 28 are secured to a pair of levers 29 and 30, pivoted around pins 31 and 32. A screw 33 is provided with a head 34 adapted to engage the ends of the levers 29 and 30 as can readily be seen by reference to Figure 3. It will be observed, by reference to Figure 4, that the collar form buck extension 20 is provided with a forwardly projecting portion 35, forming a recess under which the buck padding 27 may extend.

The buck padding consists of three layers, namely, a spring base member 36, a flannel pad 27 and a wool faced cotton cover 37.

The wool faced cotton cover is most frequently

renewed. When it is desired to renew this, the head is lifted, the screw 33 is unscrewed to loosen the band 28; the band is then lifted and the cover put in place, being inserted into the recess 38 formed by the projecting portion 35 of the collar form buck extension 20. The metal band 28 is then pressed down firmly, securing the cover and buck padding in place. The band 28 is itself secured by tightening screw 33, causing the head 34 to engage the levers 29 and 30, securing the band in place.

It is believed that the operation of my device will be clear from the foregoing description. It will be seen that I have accomplished the objects of my invention. I have provided a heated collar form which is an integral part of the buck. I have provided a construction in which the collar clamps and collar form need not be removed in order to repad the buck. The collar clamp is easily operated. The collar form is heated and will aid in drying the collar. The buck is easily repadded without the necessity of removing the clamp frames or other parts, resulting in a simple and time saving operation. The metal band for clamping the buck pad is such that the pressing head may be made to fit closely adjacent the collar form, pressing the entire yoke. No adjustments are needed on the clamping mechanism after the buck has been repadded, as is the case with the construction of the prior art, since the clamping mechanism is stationary and not removable. The collar clamping arms are out of the operator's way, while he is adjusting the collar and shirt to be pressed. The collar clamps are operated by a foot pedal, leaving the operator's hands free to adjust the garment to be pressed. My construction is simple, has a small number of parts which are easily replaced, when necessary.

It will be understood that certain features and sub-combinations are of utility and may be employed without reference to other features and sub-combinations. This is contemplated by and is within the scope of my claims. It is further

obvious that various changes may be made in details within the scope of my claims without departing from the spirit of my invention. It is, therefore, to be understood that my invention is not to be limited to the specific details shown and described.

Having thus described my invention, I claim:

1. A yoke press comprising in combination a hollow buck formed with an integral collar form, padding on said buck, means for holding said padding including a metal band passing around said collar form, means for tightening said metal band with its lower periphery contacting said padding to hold the same in position, a pressing head, means for passing steam into said pressing head and said buck and collar form, a pair of collar clamping arms, means for pivoting said arms adjacent said collar form, a spring for urging said arms into collar clamping position, and pedal operated means for pivoting said collar clamping arms outwardly against the action of said spring.
2. In a yoke press having a pivoted, steam-heated head, a buck, a collar form, formed integral with said buck, means for passing steam into said buck and collar form to heat the same, padding on said buck, and means for holding said padding in position, including a metal band passing around said collar form, pivoted members attached to the ends of the band, said pivoted members provided with means for adjustably clamping the band around said form with its lower periphery extending into engagement with said padding.
3. In a yoke press, a buck having a collar form, means for securing padding to said buck including a flexible band around said collar form having a part thereof in engagement with said pad, pivoted members attached to the band, said pivoted members provided with means for securing said band in pad securing position, and means for clamping the work to said collar form.

RAYMOND J. GABLER.
